UNITED STATES PATENT OFFICE.

CHARLES A. MALCOLM, OF MINDEN, WEST VIRGINIA.

BRAKE-SHOE.

972,202.

Specification of Letters Patent. Patented Oct. 11, 1910.

Application filed February 14, 1910. Serial No. 543,720.

To all whom it may concern:

Be it known that I, CHARLES A. MALCOLM, a citizen of the United States, residing at Minden, in the county of Fayette and State 5 of West Virginia, have invented certain new and useful Improvements in Brake-Shoes, of which the following is a specification, reference being had to the accompanying drawings.

10 This invention relates to certain new and useful improvements in brake shoes for car wheels and has for its object to provide a device of this character which will automatically true the peripheries of the wheels 15 without necessitating their removal from the trucks.

Another object is to provide a very simply constructed brake shoe which is adapted to carry an emery block for engagement upon 20 the periphery of the wheels, the brake shoe proper being so formed as to prevent movement of the emery block between itself and the car wheel flange.

With these and other objects in view, the 25 invention consists of the novel features of construction and the combination and arrangement of parts hereinafter fully described and claimed, and illustrated in the accompanying drawings, in which—

30 Figure 1 is a side elevation of my improved brake shoe engaged with the periphery of the car wheel; Fig. 2 is a section taken on the line 2—2 of Fig. 1; Fig. 3 is a detail perspective view of the emery block holder; 35 and Fig. 4 is a similar view of the emery block.

Referring more particularly to the drawings 5 indicates the brake shoe proper which is in the form of an arcuate plate having its 40 ends flanged, as at 6. One of the longitudinal curved edges of the plate 5 is also flanged, as shown at 7, and the inner face of the end flange is beveled or inclined, as shown at 8. These beveled inner faces of the 45 flanges 6 are adapted to be engaged by the ends of the emery block whereby the same will be retained in its engaged position upon the periphery of the car wheel, as will more clearly hereinafter appear. This plate 5 50 which forms the body of the shoe has integrally formed therewith upon its center a boss or knuckle 9 which is adapted to be connected or fastened to the brake mechanism, said mechanism being operated in any 55 usual or well known manner.

The emery block 10, as clearly shown in

Fig. 4, is of substantially the same curvature as the body plate 5 and is adapted to be received between the end flanges 6 thereof. The ends of this emery block are formed 60 with the transverse V-shaped grooves 11. One of the inclined walls 11 of each of these grooves is adapted to abut against the inclined inner faces of the end flanges 6, to prevent outward movement of the emery 65 block from the inner face of the body plate 5. It will be obvious that when the brake shoe is positioned upon the periphery of the car wheel, as shown in Fig. 1, transverse movement of the emery block will be prevented by the longitudinal flange 7 of the 70 brake shoe and the wheel flange A of the car wheel. Thus any movement whatsoever of the emery block when the shoe is engaged with the wheel is rendered impossible, and 75 until the brake mechanism is operated to withdraw the emery block beyond the periphery of the car wheel flange, the emery block 10 will be frictionally held in engagement upon the car wheel.

From the above, it will be seen that by the use of my improved brake shoe, the periphery of the car wheel may be kept absolutely true at all times while in use, thus eliminating the necessity of removing the 85 wheels from the trucks when the same become worn and require truing. The peripheries of the car wheels often become so far worn from contact with the rails that they are grooved and the truing of the wheels by 90 the application of an emery or other grinding stone thereto after removing the same from the trucks is a very expensive and tedious process. By means of my improved 95 brake shoe, the wheel is automatically trued while in use and the hard labor heretofore required in the truing of car wheels is entirely dispensed with.

While my improved brake shoe is more particularly adapted for use upon the wheels 100 of mine locomotives, it will be understood that, I do not wish to limit myself to such application of the device as it may also be advantageously used for many other purposes. The wheels of electrically operated 105 mining cars are, however, often chilled so that hard spots occur upon the tread faces thereof and these hard spots will eventually cause the face of the emery which bears upon the wheel to become uneven. It is then necessary to change the position of the 110 emery block in the brake shoe by withdraw-

ing the shoe from contact with the wheel and removing the emery block so that the same may be turned end for end and replaced so that the hardened or chilled part 5 of the wheel may contact with a different part of the emery block, or the block, if desired, may be secured in a different brake and replaced by an entirely new one. The emery blocks are, of course, cut in accordance 10 to the diameter of the particular wheels to which they are applied. If found desirable metallic blocks may also be used.

The construction of the brake shoe is susceptible of various other minor modifications 15 without materially departing from the essential features or sacrificing any of the advantages thereof.

It will be obvious that a brake shoe constructed as above set forth may be applied 20 to many other useful purposes other than that specified. Owing to the fact that the brake block may be readily renewed when the same becomes so worn as to affect its further utility, the same may be replaced at 25 an insignificant cost by simply removing the block from the shoe. In other forms of brake shoes as heretofore constructed, it has been necessary to discard the entire shoe after an extended period of use, and to replace 30 the same by an entirely new shoe which is quite expensive. With my device, the brake blocks may be manufactured and sold separately from the shoe so that the usefulness of the shoe may be indefinitely prolonged 35 at an insignificant expense. It will be obvious that owing to the fact that the block can be turned end for end in the shoe, its life will thus be considerably lengthened.

Having thus described the invention what 40 is claimed is:

1. A brake shoe comprising an arcuate body plate having a flange at each end, an emery block removably secured between said end flanges, a longitudinal flange formed on 45 said plate extending upon one edge of the block, said emery block being adapted for engagement upon the periphery of a wheel, whereby the same will be retained in position thereon between the longitudinal flange and the peripheral flange of the wheel.

2. A brake shoe comprising a body plate having a lateral flange formed on each end, an emery block engaged with the inner face of said plate between the end flanges, said block extending beyond said flanges for engagement upon the periphery of a wheel, and a longitudinal flange formed on said plate extending upon one edge of the block whereby said block will be retained in engagement with the wheel between said flange 60 and the peripheral flange of the wheel. 55

3. A brake shoe comprising a body plate having a lateral flange formed on each end, an emery block seated against the inner face of said plate and formed with an inclined portion on each of its ends, the inner faces of the end flanges of said plate being engaged with the inclined end portions of the block, a flange formed upon one of the longitudinal edges of the plate disposed over one 70 edge of the block, said block being adapted to be engaged with the periphery of a wheel and held thereagainst between said longitudinal flange and the wheel flange. 65

4. A brake shoe comprising a body plate 75 having a lateral flange formed on each end, the inner face of each of said flanges being inclined, a longitudinal flange formed upon one edge of said plate, an emery block disposed upon the inner face of said plate and 80 having a V-shaped groove in each of its ends, one of the inclined walls of said grooves being engaged upon the inner faces of said end flanges, said emery block extending beyond the flanges, a longitudinal flange 85 formed on one edge of the body plate disposed over the edge of the emery block, said body plate and block being arcuate in form, the outer face of the inner block being adapted for engagement upon the periphery of a 90 wheel, said block being held against accidental movement on the wheel by the longitudinal flange of the body plate and the wheel flange.

In testimony whereof I hereunto affix my 95 signature in the presence of two witnesses.

CHARLES A. MALCOLM.
